UNITED STATES PATENT OFFICE.

NILS F. SANDELIN, OF NEW YORK, N. Y., ASSIGNOR TO HIMSELF, EDWARD O. JENKINS, OF SAME PLACE, AND JOHN PAULSON, OF VASA, MINN.

IMPROVEMENT IN COTTON-PICKERS.

Specification forming part of Letters Patent No. 124,978, dated March 26, 1872.

SPECIFICATION.

I, NILS F. SANDELIN, of the county and State of New York, have invented a new and Improved Machine for Picking Cotton, of which the following is a specification:

My invention has for its object to effect a great saving of labor by picking cotton by means of a machine mounted on wheels and drawn by two horses; and also to effect a saving of the staple by picking only the ripe cotton. This is accomplished by means of a series of revolving arms or reels, provided with bristles or brushes, and laterally adjustable on a shaft, which receives its motion from the main wheels by intermediate belting or gearing. To the said reel-brushes, revolving as the machine moves forward, the cotton adheres and is again deposited on or taken off by a series of stationary arms, also provided with bristles, and attached to the frame work of the machine, from which arms it is raked off by means of adjustable rakes, also provided with bristles, and lastly deposited in a bag suspended in a suitable position on the frame. The raking is done by two persons standing on a platform in the rear part of the machine. The horses are hitched one in front of each wheel, and thus walk in the furrows on either side of the drift or row of plants, which latter thus always occupy a position directly under and parallel with the center line of the machine. My invention also relates to the construction and arrangement of the various parts, as will be hereinafter more fully described.

In the accompanying drawing, Fig. 1 represents a top or plan view of my improved cotton-picker, of about one-sixteenth of the full size. Fig. 2 is a side elevation of the same, partially sectioned through the line $x-x$ of Fig. 1. Fig. 3 is a side view of the adjustable cotton-rake. Fig. 4 is a front view of the same, in the direction of the arrow in Fig. 3.

Similar letters of reference indicate like parts.

A is the general frame-work of the machine, consisting of two inner beams, a , two outer beams, a^1 , the curved front cross-braces a^2 and a^3 , the uprights a^4 and a^5 , rear cross-beam a^6 , and platform a^7 . The braces a^2 and a^3 reaching across the longitudinal inner beams a are made in the form of an arch of sufficient ele-

vation in the center to pass clear of the cotton-plants when the picker is in operation. To the center of a^2 is pivoted a bar, B, for attaching the horses. To the center of a^3 is pivoted another cross-bar, C, to the ends of which are movably attached the rods b , sliding in the slotted uprights a^4 on the beams a , one on either side of the machine, to which rods b are attached the whiffletrees c . The bar C, rods b , and whiffletrees c , together, constitute a draft-equalizer for the horses, which equalizer I will call D. Between the beams a and a^1 , and mounted in bearings on the same beams, are placed the wheels E and E', to the axles of which are rigidly attached the pulleys d, connected by belts to other pulleys e, which are keyed on the shaft F, which carries the picking-reels. This shaft F is supported in bearings on loose beams G, the ends of which fit in slots and are adjustable in holes f in the uprights a^4 and a^5 of the frame A, for the purpose of raising and lowering the shaft F, and, thereby, also the picking-reel, according to the height of the drill of cotton-plants. The friction-rollers f' and g serve to tighten the belts on the pulleys d and e. The latter roller g is pivoted to a bar, g', sliding in a guide on the beam G, and operated by the adjustable lever H, so that the roller g may be withdrawn from the belt and the wheel E' run loose—that is, independent of the other wheel E in turning a curve as in turning the machine in on a new row or drill after finishing the picking of another. The whole length of the shaft F, between its bearings is made square, to receive and cause to revolve with it the square hubs h, of the picking-reels I, which may be slid along on the shaft F, and secured to the same at any suitable distances apart by means of the set-screws i. The reels are furthermore secured and braced in position by the stays i', which may be provided with collars and set-screws between each reel if necessary. Each of these reels consists of a number of thin, flat curved arms, having a common square hub, h. These arms serve as backing for brushes, bound in thin plates, covering and secured to the said arms on either side. By adjusting the reels I at proper distances apart, on the shaft F, they will, in revolving, as the machine moves forward, inclose the plants between these

brushes, and when the bristles have the proper stiffness will brush off only the ripe cotton, which is easiest separated, and which will adhere to the bristles and be carried up with the upward movement of the reel, and deposited on the stationary reel-cleaners J attached to the upright a^5 of the frame A. These reel-cleaners are constructed with brushes or bristles on either side, similar to the arms of the reels I, and are laterally adjustable by bolts and nuts securable in slots to the horizontal cross-beam of the upright a^5 . The reel-cleaners J are prevented from lateral deviation, by bending from their true position, by stays or braces h^2 , attached to their forward ends, and secured adjustably in slots to the horizontal cross-beam of the upright a^4 . The reel-cleaners J are set at such distances apart that each of them will, as the reels revolve, pass between the two inner sides of two of the arms thereof, the bristles on either side of the reel-cleaner J sweeping off the cotton from the bristles of the inner opposite sides of the reels I. The proportional sizes of the pulleys d and e are such that the picking-reels will make not more than one revolution for two of the wheels E E', or such that either of two men standing (one at each side of the machine) on the platform a^7 , will have time, alternately, to pass one brush-rake, K, with its bristled prongs k , (Figs. 3 and 4,) between the reel-cleaners J, just at the moment when one set of arms of the reels have passed the cleaners J, and before the next set will be in position to prevent the raking. The brush-rake K is so constructed that, on a square rod, attached to the handle of the rake, the prongs k , provided with brushes or bristles on either side, and a square hollow hub with set-screw at their upper end, to fit the said square rod, may be slid on the said rod and

secured in proper position, to enter between the cleaners J, and engage in their bristles for removing the cotton deposited on them. In pulling out the rake K from between the cleaners J, the bristles on the prongs k of the rake will engage with the bristles j' on the vertical part of the cleaners J, and thus the cotton fibers will leave the rake and adhere to the brushes j' , from which they are then swept down by hand into a bag, l , underneath the brushes j' ; said bag being suspended on hooks to the frame L, attached to the upright a^5 of the general machine frame A. M is a frame, with seat and foot-board for the driver. N is another frame for attaching an awning, to protect as well the driver as the rakers from the rays of the sun.

Claims.

1. The picking-reels I and the reel-cleaners J, constructed as described, in combination with each other and with the shaft F, and upright a^5 of the frame A, substantially as specified.
2. The combination of the lever H, sliding-bar g' , and friction-roller g with the adjustable beam G, pulleys e and d , wheel E', and frame A, substantially as specified.
3. The brush-rake K, constructed as described, for removing the cotton from the picking-reel cleaners J, substantially as specified.
4. The arrangement of the draft-equalizer D and bar B, with the arched braces a^2 a^3 , and the beams a of the frame A, substantially as specified.

The above specification of my invention signed by me this 18th day of July, 1871.

NILS F. SANDELIN.
